UNITED STATES PATENT OFFICE.

GIUSEPPE BELLUZZO, OF MILAN, ITALY.

ELASTIC-FLUID TURBINE.

No. 814,423.

Specification of Letters Patent.

Patented March 6, 1906.

Application filed August 24, 1905. Serial No. 275,559.

To all whom it may concern:

Be it known that I, GIUSEPPE BELLUZZO, a subject of the King of Italy, residing at 1 Via Paolo Frisi, Milan, Italy, have invented certain new and useful Improvements in Elastic-Fluid Turbines; and I do hereby declare the following to be a full, clear, and exact description of the invention, such as will enable others skilled in the art to which it appertains to make and use the same.

My invention relates to improvements in elastic-fluid turbines in which a plurality of bucket-wheels is arranged to receive successively the jet or fluid and in which the pressure of the fluid is almost entirely converted into velocity by expanding-nozzles before being delivered to the buckets of the wheels, while comparatively little expansion takes place in the wheels and in the guiding members; and my invention relates to turbines of this class in which the nozzle-sections are arranged about the entire periphery of the rotating members or about a part only of the same.

The object of my invention is to increase the efficiency of turbines of this class by decreasing the loss resulting from sudden changes of the direction of the jet of fluid and at the same time by guiding the jet of fluid in a more perfect way.

With this object in view my invention consists, first, in constructing the sections of the nozzle and of the successive guiding members with gradually-decreasing angles of delivery, whereby the jet of fluid is discharged into the successive bucket-wheels at different angles and in varying the height of the buckets and their distance from one another in the successive wheels; as will be more fully explained hereinafter.

A second feature of my invention relates to turbines in which the nozzle and the guiding members are arranged about a part only of the periphery of the rotating members; and my improvement consists in certain novel means to avoid the loss occurring in each of the passages formed by the buckets of the rotating members whenever they leave the sphere of the nozzles or of the guiding members and pass the cut-off portions of the same.

A third feature of my invention relates particularly to steam-turbines, and is designed to avoid the decrease of the efficiency of the machine resulting from the friction caused

by the precipitation of condensed steam on the inner walls of the casing.

For the purpose of illustrating my invention I have shown an example of a turbine embodying my improvements in the accompanying drawings, in which—

Figure 1 is a partial section of my improved turbine parallel to the axis of the same, and Fig. 2 is a circumferential section of the same developed into a plane.

Similar letters of reference refer to similar parts throughout the different views.

In the present example I have illustrated a steam-turbine in which the nozzle and the guiding members are arranged about a part of the periphery of the rotating members and in which the flow of fluid is substantially parallel to the axis of the turbine. The said turbine comprises a stationary nozzle *c*' and sectional stationary members *c*², *c*³; and *c*⁴, having steam-guiding members *d*² *d*³ *d*⁴ and rotating members or wheels *r*' *r*² *r*³, provided with buckets *f*' *f*² *f*³ *f*⁴, arranged to coöperate with said nozzles and guiding members. The rotating members are mounted on a common shaft, as is usual in the art, and their number will, for practical purposes, vary from three to six, according to the power to be developed by the turbine and the speed at which it is designed to run. In the present instance, however, I show four rotating members and accordingly three guiding members apart from the nozzle. The nozzle *c* comprises two nozzle-sections *d*' *d*', the walls of which diverge from the throat to the discharge end, whereby the fluid is expanded almost entirely to the pressure of the exhaust or of the condenser in case of a steam-turbine, while very little expansion occurs in the succeeding guiding members. The nozzle *c* may be provided with a slide-valve *p* to regulate the amount of steam admitted to the turbine.

The guiding members *d*², *d*³, and *d*⁴ are provided with properly-shaped blades to receive the jets of steam discharged from the passages of the bucket-wheels and to direct them properly into the passages of the succeeding wheels. The buckets of each of the guiding members are of any preferred construction, with exception, however, of the last one that will be explained hereinafter. The discharge ends of the blades of consecutive guiding members are arranged with different angles of delivery, said angles decreasing from the

steam inlet toward the outlet, whereby the jets of the steam are delivered to the buckets of the consecutive wheels at decreasing angles to the plane of the wheel, the angle of 5 the jet discharged from the nozzle being the largest one and being not smaller than fifty degrees.

The buckets or blades $f' f^2 f^3 f^4$ of the different wheels are of any known construction 10 and are mounted on the wheels $r' r^2 r^3 r^4$ in any preferred manner. The inlet portions of said blades of consecutive wheels are arranged at decreasing angles to their line of travel, corresponding to the decreasing incline of the discharge portions of the guiding-blades. It will appear, therefore, that the angle B of the direction of the jet of steam to the line of travel of the wheel or the angle of 15 inflow decreases from the steam-inlet, where 20 it is not less than fifty degrees toward the outlet. I also manufacture the buckets of the consecutive wheels with decreasing width, which means in the case of a turbine with axial flow the dimension of the buckets parallel to the axis of the turbine and which in the 25 accompanying drawings is designated by the letter h . The width h has its largest value in the first wheel and decreases gradually toward the last one, where it should not be less than one inch and one-sixth. In turbines 30 built heretofore buckets have been used the height of which was less than one inch and one-sixth. I have found, however, that the operation of such buckets is not satisfactory. 35 Corresponding to the decrease of the width of my improved buckets and in the same ratio I also decrease the distance of the buckets of the different wheels from one another, whereby the wheel r' is provided with a comparatively small number of buckets and the wheel r^4 with a large number.

I have found that by varying the angle of delivery into the bucket and the width and the spacing of the buckets of the different 45 wheels in the manner stated above I increase the efficiency of the turbine by improving the travel of the fluid through the buckets of the wheels and of the guiding members.

50 It is apparent that the improvements explained above with reference to a steam-turbine, in which the nozzles are arranged about a part only of the periphery, will have the same beneficial results in turbines designed 55 for the use of any other elastic fluid, as motive power, and in turbines in which the nozzle-sections are arranged about the entire periphery.

The second feature of my invention refers 60 particularly to turbines in which the nozzles are arranged about a part only of the periphery of the wheels. I have discovered that in turbines of this class much loss results from the fact that the canals formed by 65 the buckets of the wheels when they leave

the sphere of the fluid jets receive their last jet at a time when their outlet-passage has just passed the cut-off edge of the next following guiding member, whereby said jet cannot escape into the last canal of the following 70 guiding member, and thereby impart its energy to the rotating wheel. Now to avoid this disadvantage I arrange the guiding members in such way that the outlet-passages of the bucket-wheels is still almost entirely open at the moment when its inlet-passage is cut off by the preceding guiding member or nozzle, and to effect this I curve the wall of the guiding members that forms the cut-off edge backward, so as to register with the discharge portion of the preceding bucket when the inlet portion of the succeeding bucket just passes the cut-off edge of the preceding guiding member. The said wall of 75 said guiding members will therefore have a 80 strongly-curved form, as shown at $a b$ in Fig. 2 of the drawings. In co-operation herewith it will generally be necessary to cut off a part of the last blade of the guiding members at its discharge end in order to secure a free and 85 unobstructed passage for the discharged fluid. It is apparent that the aforesaid improvement is applied only to the guiding members and not to the nozzle-sections.

The third feature of my invention refers 90 particularly to steam-turbines, and its purpose is to avoid the precipitation of condensed steam on the inner walls of the casing, which condensed steam would offer considerable resistance to the blades. For this purpose 95 I provide the members c^2 , c^3 , and c^4 with a jacket having a steam inlet and outlet. Now preferably some time before starting the turbine I admit steam to said jacket and 100 heat the turbine, whereby condensation of 105 steam is avoided.

The operation of my improved turbines will be readily understood from the description of its parts. It does not vary in any respect, save efficiency, from turbines heretofore in use.

Having thus fully described my invention, what I claim as new, and desire to secure by Letters Patent of the United States, is—

1. In elastic-fluid turbines, the combination with a nozzle, of a plurality of bucket-wheels arranged successively to receive the motive fluid, the angles of delivery into the bucket-wheels and the angles of the inlet portions of the buckets of the several bucket-wheels to the line of travel of said wheels being arranged to decrease from the nozzle side toward the exhaust side of the turbine.

2. In elastic-fluid turbines, the combination with an expanding-nozzle arranged to convert the pressure of the fluid into velocity, of a plurality of bucket-wheels arranged successively to receive the motive fluid, the angles of delivery into the bucket-wheels and the angles of the inlet portions of the buckets

- of the several bucket-wheels to the line of travel of said wheels being arranged to decrease from the nozzle side toward the exhaust side of the turbine.
5. In elastic-fluid turbines, the combination, with an expanding-nozzle arranged to convert the pressure of the fluid into velocity, of a plurality of bucket-wheels arranged successively to receive the motive fluid, and fluid-guiding members, said nozzle and guiding members having their angles of delivery into the bucket-wheels arranged to decrease successively from the nozzle to the last of the guiding members, and the buckets of said bucket-wheels having the angles of their inlet portions to their line of travel arranged to decrease from the nozzle side toward the exhaust side of the turbine.
10. In elastic-fluid turbines, the combination, with an expanding-nozzle arranged to convert the pressure of the fluid into velocity, of a plurality of bucket-wheels and fluid-guiding members, said nozzle and guiding members having their angles of delivery into the bucket-wheels arranged to decrease successively from the nozzle to the last of the guiding members, and the buckets of said bucket-wheels having the angles of their inlet portions to their line of travel arranged to decrease from the nozzle side toward the exhaust side of the turbine.
15. In elastic-fluid turbines, the combination, with an expanding-nozzle arranged to convert the pressure of the fluid into velocity, of a plurality of bucket-wheels, and fluid-guiding members, said nozzle and guiding members having their angles of delivery into the bucket-wheels arranged to decrease successively from a value of substantially fifty degrees in the nozzle to the last one of the guiding members, and the buckets of said bucket-wheels having the angles of their inlet portions to their line of travel arranged to decrease from the nozzle side toward the exhaust side of the turbine.
20. In elastic-fluid turbines, the combination, with an expanding-nozzle arranged to convert the pressure of the fluid into velocity, of a plurality of bucket-wheels, and fluid-guiding members, said nozzle and guiding members having their angles of delivery into the bucket-wheels arranged to decrease successively from a value of substantially fifty degrees in the nozzle to the last one of the guiding members, and the buckets of said bucket-wheels having the angles of their inlet portions to their line of travel arranged to decrease from the nozzle side toward the exhaust side of the turbine.
25. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
30. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
35. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
40. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
45. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
50. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
55. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
60. In an elastic-fluid turbine, the combination, with a nozzle, of a plurality of bucket-wheels and fluid-guiding members arranged to receive successively the motive fluid, the buckets of consecutive wheels having their width decreasing from the inlet side to the exhaust side of the turbine.
65. In an elastic-fluid turbine, the combination, with a nozzle, of a plurality of bucket-wheels and fluid-guiding members arranged to receive successively the motive fluid, the buckets of consecutive wheels having their width and their distance from one another decreasing from the inlet side to the exhaust side of the turbine.
70. In an elastic-fluid turbine, the combination, with a nozzle, of a plurality of bucket-wheels and fluid-guiding members arranged to receive successively the motive fluid, the buckets of consecutive wheels having their width and their distance from one another decreasing from the inlet side to the exhaust side of the turbine, the width of the buckets of the last wheel being not less than one inch and one-sixth.
75. In an elastic-fluid turbine, the combination, with a nozzle, of a plurality of bucket-wheels and fluid-guiding members arranged to receive successively the motive fluid, the buckets of consecutive wheels having their width and their distance from one another decreasing from the inlet side to the exhaust side of the turbine, the width of the buckets of the last wheel being not less than one inch and one-sixth.
80. In an elastic-fluid turbine, the combination, with a nozzle, of a plurality of bucket-wheels and fluid-guiding members arranged to receive successively the motive fluid, the buckets of consecutive wheels having their width and their distance from one another decreasing substantially in the same ratio from the inlet side toward the exhaust side of the turbine.
85. In an elastic-fluid turbine, the combination, with a nozzle, of a plurality of bucket-wheels and fluid-guiding members arranged to receive successively the motive fluid, the buckets of consecutive wheels having their width and their distance from one another decreasing substantially in the same ratio from the inlet side toward the exhaust side of the turbine.
90. In an elastic-fluid turbine, the combination, with a nozzle, of a plurality of bucket-wheels, of a guiding member arranged about a part of the periphery of said bucket-wheels, said guiding member having guiding-blades and having its cut-off wall curved backward in the direction of the travel of the rotating member discharging into the same at an angle smaller than that of said guiding-blades to such an extent that the outlet of each of the passages of said rotating member is still open when its inlet is cut off.
95. In an elastic-fluid turbine, the combination, with a nozzle, of a plurality of bucket-wheels, of a guiding member arranged about a part of the periphery of said bucket-wheels, said guiding member having guiding-blades and having its cut-off wall curved backward in the direction of the travel of the rotating member discharging into the same at an angle smaller than that of said guiding-blades to such an extent that the outlet of each of the passages of said rotating member is still open when its inlet is cut off.
100. In an elastic-fluid turbine, the combination, with a nozzle, of a plurality of bucket-wheels, of a guiding member arranged about a part of the periphery of said bucket-wheel, said guiding member having guiding-blades and having its cut-off wall curved backward in the direction of the travel of the rotating member discharging into the same at such an extent that the outlet of each of the passages of said rotating member is still open when its inlet is cut off, the last of said blades of the guiding members having a part of its discharge end cut away.
105. In an elastic-fluid turbine, the combination, with a nozzle, of a plurality of bucket-wheels, of a guiding member arranged about a part of the periphery of said bucket-wheel, said guiding member having guiding-blades and having its cut-off wall curved backward in the direction of the travel of the rotating member discharging into the same at such an extent that the outlet of each of the passages of said rotating member is still open when its inlet is cut off, the last of said blades of the guiding members having a part of its discharge end cut away.
110. In an elastic-fluid turbine, the combination, with a nozzle, of a plurality of bucket-wheels, of a guiding member arranged about a part of the periphery of said bucket-wheel, said guiding member having guiding-blades and having its cut-off wall curved backward in the direction of the travel of the rotating member discharging into the same at such an extent that the outlet of each of the passages of said rotating member is still open when its inlet is cut off, the last of said blades of the guiding members having a part of its discharge end cut away.
115. In testimony whereof I affix my signature to this specification in the presence of two witnesses.

GIUSEPPE BELLUZZO.
